UNITED STATES PATENT OFFICE.

PAUL W. KREUZKAMP, OF BROOKLYN, NEW YORK, ASSIGNOR TO ENGLANDER SPRING BED COMPANY, OF BROOKLYN, NEW YORK, A CORPORATION OF NEW YORK.

COLLAPSIBLE BED.

1,119,835.

Specification of Letters Patent. Patented Dec. 8, 1914.

Application filed April 6, 1914. Serial No. 829,724.

To all whom it may concern:

Be it known that I, PAUL W. KREUZKAMP, a citizen of the United States, residing at Brooklyn, in the county of Kings and State 5 of New York, have invented certain new and useful Improvements in Collapsible Beds, of which the following is a specification.

This invention relates to folding beds, it 10 having more particularly to do with the making practical of a certain form of collapsible bed, and it is easier and less dangerous to operate.

In the drawings accompanying and forming 15 part of this specification, Figure 1 is a perspective view of the improved form of bed with which the present improvement has to do, and Fig. 2 is a detailed enlarged view of one corner of the bed showing the 20 same partly folded.

Similar characters of reference indicate 25 corresponding parts throughout the figures of the drawings.

The improved folding bed with which the 30 present improvement has to do comprises a pair of end frames consisting of a head 2 and a foot 3 to which is secured brackets 4 having inwardly extending arms 5, the inner ends 6 of which are pivotally connected 35 to a mattress frame 7 comprising a pair of side-bars 8 to which at the ends thereof is secured transverse bars 9 between which the mattress proper 10 is hung. The head and foot members 2 and 3 are provided with pivoted legs or feet 11, a pair at each end of the structure being connected or braced by a bar 12 and the lower ends of these legs carry casters or rollers 13. Extending from the lower end of the legs to the side-bars 40 are diagonal braces 14, the inner end of each brace being connected by a rivet or bolt 15 with a link 16, the opposite end of which in turn is pivoted to the bracket 4. The side-bars are shown provided with slots 17 45 through which the connecting bolts between the diagonal braces and the links pass and in which slots such bolts move when the head and foot are folded. This structure

thus permits the head and foot to be folded in the manner partly shown in Fig. 2 thereby drawing the pivoted legs upward in such position that the rollers or casters will still remain on the floor so that in either the form shown in Fig. 1 or the form in which the bed is folded into its folded position, it 50 may be readily shifted on the same casters under another bed or out of the way. For locking the mattress frame in its normal bed position suitable locking means is provided, this consisting of locking bolts 60 adapted to project into openings 18 in the brackets, these bolts being withdrawn by some suitable spring clip 19 thereby to lower the bed. This folding bed, however, has been proven in practice to be difficult to 65 manipulate, especially for a woman, and also dangerous in that when the locking bolts are released the weight of the mattress frame is such that it immediately falls with a bang to the injury of the floor and 70 not only this, but it is likely to injure the operator should his feet be under the mattress frame when it suddenly descends as has been found in practice to be frequently 75 the case. Not only this, but it is difficult for a woman to raise the mattress frame back into its normal bed position owing to the weight of the parts. To overcome these difficulties I have provided means whereby 80 the bed will descend gradually so that there is no liability of it injuring either the feet of the operator or the floor and whereby also the bed can be readjusted into its normal bed position by comparatively little effort on the part of the operator. This 85 means in the present instance consists of a set of springs, four in number, located in a particular manner so that the object sought will be accomplished. Each spring in the present instance comprises a coil 90 spring 20 having one end secured to the side-bar and its opposite end secured to the bolt which connects the diagonal brace and the link, or instead of to the bolt to a bent or inwardly extending end 21 of the diagonal brace, as shown in Fig. 2. By this 95

means when the locking bolts are released it has been found that the springs through their co-action with the side-bars and the sliding inner ends of the diagonal braces and links causes the mattress frame to descend gradually and slowly to a certain point, after which it may be pushed down to the floor, the springs thus preventing the descent of the mattress frame too quickly and in fact necessitating after the mattress frame has partially descended that it be pushed down the rest of the distance, and as these springs are under their full tension when the bed is folded it follows that when it is desired to raise the mattress this may be readily done by very little effort since the springs materially assist in the upward movement of the bed frame. Thus the liability of injury to the floor or to the operator is entirely avoided, while at the same time very little strength is now required to lift the heavy mattress frame.

I do not make any claim herein to the folding bed structure *per se*, as this is not a part of my invention. I only claim the means for making the bed practical and permitting it to be operated without danger to the operator and with increased effectiveness.

30 I claim as my invention:

1. A folding bed comprising a descendible mattress frame shiftable up and down in a horizontal plane, folding head and foot members pivotally connected to said mattress frame for supporting it, means connecting said head and foot members with the mattress frame and shiftable relatively to the latter, and means for facilitating the raising and lowering of the mattress frame.

40 2. A folding bed comprising a descendible mattress frame shiftable up and down in a horizontal plane, folding head and foot members pivotally connected to said mattress frame for supporting it, means connecting said head and foot members with the mattress frame and shiftable relatively to the latter, and springs for facilitating the raising and lowering of the mattress frame.

3. A folding bed comprising a descendible mattress frame shiftable up and down in a horizontal plane, folding head and foot members pivotally connected to said mattress frame for supporting it, means connecting said head and foot members with the mattress frame and shiftable relatively to the latter, and means connected to said last means and with the mattress frame for facilitating the raising and lowering of the mattress frame.

50 4. A folding bed comprising a descendible mattress frame, folding head and foot members pivotally connected to said mattress frame for supporting it, means connecting said head and foot members with the mat-

tress frame and shiftable relatively to the latter, and springs connected to said last means and with the mattress frame for facilitating the raising and lowering of the mattress frame.

5. A folding bed comprising a descendible mattress frame, folding head and foot members pivotally connected to said mattress frame for supporting it, means connecting said head and foot members with the mattress frame and shiftable relatively to said frame, and coil springs connected with said shiftable means and with the mattress frame for facilitating the raising and lowering of the mattress frame.

6. A folding bed comprising a descendible mattress frame having slotted side-bars, folding head and foot members pivotally connected to said mattress frame for supporting it, connections between said head and foot members and the mattress frame, the inner ends of said connections sliding in the slots of said side-bars, and coil springs connected with the inner ends of said connections and with said side-bars for facilitating the raising and lowering of the mattress frame.

7. A folding bed comprising a descendible mattress frame having slotted side-bars, head and foot members pivotally connected with said side-bars, feet pivotally connected with said head and foot members, links extending from the head and foot members and from the feet, each pair thereof connected at their inner ends by means passing through a slot of the side-bar, and means connecting such inner ends with the side-bars for facilitating the raising and lowering of the mattress frame.

8. A folding bed comprising a descendible mattress frame having slotted side-bars, head and foot members pivotally connected with said side-bars, feet pivotally connected with said head and foot members, links extending from the head and foot members and from the feet, each pair thereof connected at their inner ends by means passing through a slot of the side-bar, and means connecting such inner ends with the side-bars for facilitating the raising and lowering of the mattress frame, said means comprising coil springs.

9. A folding bed comprising a descendible mattress frame having slotted side-bars, folding head and foot members provided with brackets, each pivotally connected to a side-bar, feet pivotally connected to the head and foot members and having at their lower ends casters or rollers, a link extending from each bracket to the side-bar, a link extending from each foot to the side-bar, means passing through a slot of the side-bar for connecting said links, and a coil spring connected with said links at their points of connec-

tion and with the side-bar for facilitating the raising and lowering of the mattress frame.

10. A folding bed comprising a descendible mattress frame, folding head and foot members pivotally connected to said mattress frame for supporting it, connections between said head and foot members and the mattress frame and shiftable relatively to

the latter, and coil springs connected with 10 said connections and with the side-bars and extending in the direction of the length of the side-bars for facilitating the raising and lowering of the mattress frame.

PAUL W. KREUZKAMP.
